UNITED STATES PATENT OFFICE.

ELIHU E. GABBART, OF KINGSLAND, TEXAS, ASSIGNOR OF ONE-HALF TO CLYDE HAILE, OF KINGSLAND, TEXAS, TOGETHER HAVING INVENTED A RAILWAY SIGNAL SYSTEM.

No. 888,483.

Specification of Letters Patent. Patented May 26, 1908.

Application filed October 16, 1907. Serial No. 397,712.

To all whom it may concern:

Be it known that I, ELIHU E. GABBART, a citizen of the United States, residing at Kingsland, in the county of Llano, State of Texas, have invented certain new and useful Improvements in Railway Signal Systems, and I do hereby declare the following to be a full, clear, and exact description of the invention, such as will enable others skilled in the art to which it appertains to make and use the same:

This invention relates to railway signal systems and more particularly to a system of this class which is designed principally for use on curves where it is desirable to indicate at one end of the curve when a train enters the opposite end of the curve. The invention, however, is not restricted to this specific use and may be employed under many other conditions such for example at railroad crossings and railroad and highway crossings.

One of the primary objects of my invention is to provide, in connection with the system of wiring, a novel form of circuit closer which is so constructed that it will act positively and effectually at the time of passage of a train and will not be liable to injury by reason of the sudden impact of the car wheels therewith. This latter result I attain by providing, against one side of the tread of the outer rail of the track curve, a plate which is so mounted that the passage of the wheel flanges therebetween and the said side of the tread will move the plate away from the said tread and result in the depression of a contact leaf, this depression of the leaf serving to close the circuit through the wiring and through a lamp positioned at the opposite end of the curve, it being understood that one or more of these circuit closing devices is located at each end of the curve and that in a like manner a signal lamp is located at each end of the curve.

In the accompanying drawings, Figure 1 is a top plan view of a track curve showing the arrangement of the system, Fig. 2 is a similar view but in detail of only one end of the curve, Fig. 3 is a side elevation of one of the circuit closing devices, the rail with which the device is associated being shown in transverse section, Fig. 4 is a detail vertical longitudinal sectional view through the circuit closing device showing the rail in transverse section and illustrating in full lines the normal position of the several members of the

device and in dotted lines their position at the time of passage of a train, Fig. 5 is a diagrammatic view of the system of wiring employed in this form of the invention, Fig. 6 is a view similar to Fig. 1 showing the application of the system to a railroad crossing, and, Fig. 7 is a diagrammatic view of the system of wiring used in this form of the invention.

In the first five figures of the drawings illustrating a system as applied to a curved section of track, the tracks are indicated by the numeral 10 and the numeral 11 indicates a tie at one end of the curve and the numeral 12 a tie at the other end thereof and it is upon these ties 11 and 12 that the circuit closing devices are to be disposed, which circuit closing device will be presently fully described.

In carrying out the invention I provide a main supply wire 13 which supplies the necessary current to the other wires of the system as will be presently made clear. This wire 13 is strung upon poles 14 and extends, of course, throughout the entire length of the curve and from a suitable supply station (not shown). A wire 15 is tapped to this main supply wire 13 at a point opposite to the tie 11 and a similar wire 16 is tapped to the main supply wire 13 at a point opposite to the tie 12. Lamps 17 and 18 are hung adjacent the ties 11 and 12 respectively and leading to the lamp 17 is a wire 19 this wire being extended from a point adjacent the tie 12 as will be presently more fully explained. A similar wire 20 is led from a point adjacent the tie 11 to the lamp 18 and leading from the lamps 17 and 18 to ground are wires 21 and 22 respectively. Each of the lamps is inclosed in a casing having on one side a white bull's eye and on the other side a red bull's eye, the white bull's eyes of the two lamps being presented in opposition or in other words in a direction toward each other and toward the opposite end of the curve to that at which the corresponding lamps are located. It will thus be seen that the engineer of a train coming in at one end of the curve will observe a red light at that end of the curve should the lamp be lighted by the entrance of a train on the curve from the opposite end.

For example, should a train enter the curve from the north, the light at the south end of the curve will be lighted and the engineer of a train approaching the curve from the south will observe a red light and will know that

the curve is occupied. The circuit closing device for producing the result stated above will now be described.

Each of the circuit closing devices mentioned above comprises a casing including sides 23, a top 24, a closed end 25 and an open end 26, which latter end is presented in the direction of the outer rail 10 of the track curve. Arranged within this casing is a pair of leaf spring contacts one of which is indicated by the numeral 27 and the other by the numeral 28 and leading into the casing, beneath the rail, are the wires, in one instance 15 and 20 and in the other instance 16 and 19, the wires 15 and 16 being connected to the contacts 27 of the respective circuit closers and the wires 20 and 19 to the contacts 28 of the respective circuit closers, it being understood, of course, that these contacts 27 and 28 are normally spaced by reason of their resiliency. Pivoted as at 29 in the casing inwardly of the contacts 27 and 28 is a head 30 formed at the inner end of an arm 31 which arm projects through the upper portion of the open end of the casing and in the direction of the rail 10 heretofore mentioned. Fixed to this head 30 is a tongue 32 which, when the arm 31 is swung downwardly upon its pivot, engages the upper contact 27 and 30 presses the same into engagement with the lower contact 28. This arm 31 is, however, normally held raised by means of a leaf spring 33 which is secured at its lower end at the lower edge of the open end of the casing and extends upwardly beneath the said arm 31. In order that the arm may be moved downwardly as above stated to bring the two contacts 27 and 28 in mutual engagement, I have provided a device beneath which the outer end of the arm extends and which is designed to be operated by the passage of the wheels of a train. This device is in the form of a plate 34 which is provided upon its end edge and adjacent each end with an eye 35 which is received between a pair of eyes 36 formed upon the web of the rail 10, there being pivot bolts engaged through the said sets of eyes. In this manner the plate 34 is mounted to swing with its upper edge away from the tread of the rail at the time of passage of the flanges of the car wheels therebetween and the said tread of the rail, the end portions of the plate being curved outwardly from the rail as at 37 to admit of the ready reception of the said wheel flanges. A tongue 38 is formed integral with the inner side of the plate 34 and this tongue projects over the arm 31, it being understood that when the plate 34 is swung upon its hinges 39 in the manner stated above, the tongue 38 will engage with the arm 31 and depress the same thereby bringing the contact 27 into engagement with the contact 28. In order that the plate 34 may be returned to its nor-

mal position after the passage of each wheel, 65 rods 39 are secured at their lower ends to the corresponding base flanges of the rail and extend upwardly therefrom and at their upper ends through U-shaped loops 40 formed upon the said plate 34 and projecting inwardly 70 therefrom. Springs 41 are engaged upon the rods 39 and it is against the upper ends of these springs that the loops 40 bear, it being understood that the springs have a normal tendency to expand and to return the plate 75 34 to its normal position as stated.

While it is true that the circuit is rapidly made and broken at the time of passage of each wheel, between the plate 34 and the tread of the wheel, the wheels of course pass 80 in such rapid succession that practically a continual light will be displayed at the other end of the curve. Should the curve be a very long one I have found it expedient to employ several of the circuit closing devices 85 which are disposed within fifty yards or so of each other and when this is done taps are taken both from the main supply wire and the corresponding wire 19 and 20 as the case may be. 90

In Figs. 6 and 7 of the drawings I have shown the application of my railway signal to a railroad crossing and in Fig. 6 one of the tracks, for example the south bound track, is indicated by the numeral 43 and the other track which is either east or west bound is indicated by the numeral 44, it being understood, of course, that these tracks intersect. In these two figures the numeral 45 indicates the main supply wire which wire is extended 100 along only one of the tracks however, as shown in the drawings along the track 44. A tap is taken from this wire by means of a wire 46 at a considerable distance upon each side of the point of intersection of the two tracks 43 and 44 and a lamp 47 is located adjacent the point of intersection of the tracks and with its red bull's eye presented in the direction of a train approaching on the south bound track. The wire 46 leads to one contact of the circuit closing device constructed as heretofore explained which device is indicated by the numeral 48 and is located beside one of the rails of the track 44 and leading to the other contact of this circuit closer 48 is a wire 49 which wire leads also to the lamp 47, there being a wire 50 leading from the lamp to ground. A similar circuit closer 51 is located adjacent one of the rails of the track 43 but to the other side of the point of intersection of the tracks 43 and 44 and leading to this circuit closer is a wire 52 which is tapped to the main supply and also a wire 53 which leads to the lamp 56. A wire 57 is tapped to the main supply and leads to one contact of a 110 circuit closer 55 located in operative relation to one of the rails of the track 43 and leading from the other contact of this circuit closer to 115 120 125

a lamp 56 disposed adjacent the point of intersection of the two tracks is a wire 57 there being a wire 58 led from the lamp to ground.

From the foregoing description of the application of the system to a railroad crossing it will be understood that the engineer of a train approaching on either of the tracks will be warned of the approach of a train on the other track.

10 What is claimed is—

1. A circuit closer for a railway signal system comprising, in combination with a rail, a casing disposed adjacent the rail, contacts within the casing, a movable member supported within the casing and having a portion engageable with one of said contacts for moving it into engagement with the other contact and having an arm extending outwardly of the casing, a plate hinged at its lower edge to the rail and adapted to be spread therefrom by the passage of a car wheel, a tongue upon the plate, which tongue overlies the arm, and means for holding the plate to normal position.

2. A circuit closer for a railway signal system comprising, in combination with a rail, a casing disposed adjacent the rail, contacts within the casing, a movable member supported within the casing and having a portion engageable with one of said contacts for mov-

ing it into engagement with the other contact and having an arm extending outwardly of the casing, a plate hinged at its lower edge to the rail and adapted to be spread therefrom by the passage of a car wheel, a tongue upon the plate, which tongue overlies the arm, and means for holding the plate to normal position.

3. A circuit closer for a railway signal system comprising, in combination with a rail, a casing disposed adjacent the rail, contacts within the casing, an arm pivoted within the casing and extending outwardly therefrom in the direction of the rail, a tongue carried by the arm and engageable with one of said contacts for moving it into engagement with the other contact, a plate hinged at its lower edge to the rail and adapted to be spread therefrom by the passage of a car wheel, a tongue upon the plate overlying the free end of said arm, and means for holding the plate to normal position.

In testimony whereof, I affix my signature, in presence of two witnesses.

ELIHU E. GABBART.
